UNITED STATES PATENT OFFICE.

FORSTER H. JENINGS, OF WASHINGTON, DISTRICT OF COLUMBIA.

DESIGN FOR AN ADVERTISING-STAND.

SPECIFICATION forming part of Design No. 24,886, dated November 12, 1895.

Application filed September 11, 1895. Serial No. 562,214. Term of patent 3½ years.

To all whom it may concern:

Be it known that I, FORSTER H. JENINGS, a citizen of the United States, residing at Washington, in the District of Columbia, have invented and produced a new and original Design for an Advertising-Stand, of which the following is a specification, reference being had to the accompanying drawing, showing a part thereof.

- In the drawing I have shown a front elevation of the device, the leading features of which consist in the representation of a platform, upon which is seated at one side a man in Turkish costume, holding in one hand a drum and in the other a drumstick. In front of the seated figure is shown a standing figure, representing a girl in Turkish dancers' costume and having her arms with hands clasped. Behind the figure of the girl is a section of scrollwork.

Referring to the drawing, a is a platform, to the right and rear of which is shown a low rail of scrollwork b, and standing in front thereof and with the face turned slightly to one side is the representation of a girl c in the 25 garb of a dancer, said garb consisting of a close-fitting shirt d, a Zouave jacket e, Turkish bloomers f, sash g, and Turkish shoes h. This female figure, moreover, is shown with the arms i raised and with the hands k clasped. 30 Directly in front of the female figure is shown a male figure in a squatting position and dressed in Turkish costume, consisting of a jacket m, trousers n, sash o, Turkish shoes p, turban r, and holding upon his knee a Turkish drum s, which is held with one hand, while the other holds a drumstick t.

Having thus described my design, what I claim is—

The design for an advertising stand, substantially as shown and described.

In testimony whereof I affix my signature in the presence of two witnesses.

FORSTER H. JENINGS.
